US00D775609S

(12) **United States Design Patent** (10) **Patent No.:** **US D775,609 S**
Lee et al. (45) **Date of Patent:** **** Jan. 3, 2017**

(54) **PORTABLE EARSET**

(71) Applicant: **LG ELECTRONICS INC.**, Seoul (KR)

(72) Inventors: **Sungho Lee**, Seoul (KR); **Joonhyung Kim**, Seoul (KR); **Kyubong Choi**, Seoul (KR)

(73) Assignee: **LG ELECTRONICS INC.**, Seoul (KR)

(**) Term: **15 Years**

(21) Appl. No.: **29/535,601**

(22) Filed: **Aug. 7, 2015**

(30) **Foreign Application Priority Data**

Feb. 9, 2015 (KR) 30-2015-0006954

(51) **LOC (10) Cl.** **14-01**

(52) **U.S. Cl.**

(57) **CLAIM**

The ornamental design for a portable earset, as shown and described.

DESCRIPTION

FIG. 1 is a perspective view of a portable earset showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a reference view thereof showing an example of the usage of the subject design.

The broken lines depict portions of the portable earset that form no part of the claimed design.
